UNITED STATES PATENT OFFICE

GLENN E. McFADDEN, OF DETROIT, MICHIGAN, ASSIGNOR TO LINCOLN MANUFACTURING COMPANY, OF DETROIT, MICHIGAN, A CORPORATION OF MICHIGAN

DESIGN FOR A CHANDELIER OR ANALOGOUS LIGHTING FIXTURE

Application filed July 22, 1929. Serial No. 32,163. Term of patent 7 years.

To all whom it may concern:

Be it known that I, GLENN E. McFADDEN, a citizen of the United States, residing at Detroit, county of Wayne, State of Michigan, have invented a new, original, and ornamental Design for a Chandelier or Analogous Lighting Fixture, of which the following is a specification, reference being had to the accompanying drawing, forming part thereof.

Fig. 1 is a side elevation of my improved chandelier or analogous lighting fixture.

Fig. 2 is a sectional view taken on the line 2—2 of Fig. 1.

Fig. 3 is a sectional view taken on the line 3—3 of Fig. 1.

It is understood that the ornamentation appearing in part on Fig. 2 is repeated over the corresponding part shown in dotted outline and that the same is true of the arm shown in dotted outline in Fig. 1.

I claim:

The ornamental design for a chandelier or analogous lighting fixture, as shown and described.

GLENN E. McFADDEN.
